(57) **CLAIM**

The ornamental design for a LED strip light, as shown and described.

DESCRIPTION

1. LED strip light

1.1 : Perspective

1.2 : Perspective

1.3 : Front

1.4 : Back

1.5 : Left

1.6 : Right

1.7 : Top

1.8 : Bottom

1.9 : Reference view of state of use

The broken lines shown in the drawings are included for the purpose of illustrating portions of the LED strip light that form no part of the claimed design; the LED strip light is flexible, which can be placed into the corresponding shape according to user's requirements.

The break lines in the drawings indicate that the appearance of any portion of the LED strip light between the break lines forms no part of the claimed design.
